UNITED STATES PATENT OFFICE.

LOUIS A. SCHMIDT, OF NEW YORK, N. Y., ASSIGNOR TO R. HOE AND CO., OF NEW YORK, N. Y., A CORPORATION OF NEW YORK.

PRINTING-MACHINE.

1,136,371.

Specification of Letters Patent. Patented Apr. 20, 1915.

Application filed July 29, 1913. Serial No. 781,766.

To all whom it may concern:

Be it known that I, LOUIS A. SCHMIDT, a citizen of the United States, residing at New York, county of Kings, and State of New York, have invented certain new and useful Improvements in Printing-Machines, fully described and represented in the following specification and the accompanying drawings, forming a part of the same.

10 This invention relates to certain improvements in printing machines.

It is the object of the present invention to provide an improved inking arrangement for such machines employing a plurality of printing couples whereby a single ink fountain and a single ink distributing cylinder or roll supplies the necessary ink to the form members of two printing couples, thus producing a very simple and compact construction.

20 For a full understanding of the invention reference may be had to the accompanying drawing and a detailed description of the same.

25 The figure of the drawing is a diagrammatic side elevation illustrating one embodiment of the invention shown as applied to a rotary perfecting press.

30 Constructions embodying the invention will include a plurality of printing couples which may be of any desired type. In the machine selected to illustrate the invention, the printing couples are rotary couples, and in the machine shown these couples are arranged in decks, two couples to a deck, each deck forming a perfecting mechanism, and two decks being arranged in line.

35 Referring to the drawing, A indicates one deck, which includes form cylinders 1 and 2, and impression cylinders 3, 4; B indicates a second deck, this deck including form cylinders 5, 6, and impression cylinders 7, 8, the cylinders of decks A and B being substantially in line; C indicates a third deck, including form cylinders 9, 10, and impression cylinders 11, 12; D indicates a fourth deck, including form cylinders 13, 14 and impression cylinders 15, 16, decks C and D having their cylinders in line and being shown as arranged below decks A, B.

40 In accordance with the invention, there is provided one inking fountain and fountain roll and a single distributing cylinder or roll for supplying ink to the form cylinders of 45 two of the rotary couples. In the particular

machine illustrated, in which the couples are arranged in decks of two couples to a deck and two decks arranged in line, the ink distributing cylinder and fountain will be preferably arranged between the last couple of 60 the first deck and the first couple of the second deck for each story of decks.

The constructions are in the machine illustrated identical and a description of one will suffice for an understanding of the invention. The ink fountain and ink distributing cylinder may be of any suitable or usual design. In the particular construction illustrated, there is provided a fountain 17 in which rotates a fountain roll 18 operated in 65 any suitable manner. From this roll 18 ink is taken by a vibrating ductor 19, which is given a vibratory movement by any suitable mechanism. This ductor delivers ink to an ink distributing cylinder 20. The ink may 70 be delivered from the distributing cylinder 20 to the form cylinders in various ways. In the particular construction illustrated, the ink from the distributing cylinder is delivered to the form cylinder 2 of the printing deck A directly by means of a pair of distributing rolls 21. The ink is delivered to the form cylinder 5 of deck B on the other side of the distributing cylinder by a pair of 75 form rolls 22. These form rolls 21, 22 are 80 preferably frictionally driven. In the construction illustrated, the distributing cylinder and form cylinder 2 are rotating in the same direction, and form cylinder 5 is rotating in the opposite direction, and as the form rolls are frictionally driven, it is necessary 85 to effect the proper inking of form cylinder 5 that the direction of rotation of the form rolls 22 be reversed. Various means may be 90 employed for reversing the direction of the rotation of form rolls 22. In the particular construction illustrated, this is effected by providing a pair of intermediate rolls 23 frictionally driven from the distributing cylinder and from which the rolls 22 are 95 frictionally driven in a direction reverse to the direction of rotation of the intermediates 23, and reverse to the direction of rotation of the form cylinder 5, whereby the form cylinder takes its ink properly. These intermediates in addition to reversing the direction of rotation of the form rolls 22, further 100 act to affect an even distribution of the ink. The parts are, therefore, preferably arranged, as shown, with the form cylinder 110

first inked from the distributing cylinder taking its ink through intermediate rolls 23 and form rolls 22, though if desired, the reverse arrangement may be adopted. A further evening of the ink distribution may be desired, which may be effected by providing a pair of the usual vibrating distributing rolls 24 operated in any suitable manner.

With this construction it is apparent that 10 a considerable saving in space and in number of parts is effected, as by such construction a fountain roll, ductor, and distributing cylinder and accompanying distributing rolls are eliminated.

15 It will be understood that the two form cylinders inked from the single distributor are supplied with sufficient ink by causing the fountain roll and ductor to operate at speeds sufficient to deliver the amount of 20 ink required or desired, this being accomplished by suitably adjusting such parts.

It will be understood that while a distributing cylinder has been shown as inking the second form cylinder of one deck 25 and the first form cylinder of a deck arranged on the other side of the distributing cylinder, this construction being especially convenient in that two webs may be perfected without turning, the distributing cylinder may be located between two printing couples of one deck where only 30 one deck of such couples is used. In such construction it will, of course, be understood that to perfect a web, the web is 35 turned, which can be effected by any suitable turning bar of ordinary construction, which has not been illustrated, as such illustration is thought unnecessary.

The form cylinders 1 and 6 of decks A 40 and B are inked in the machine illustrated, by separate inking mechanisms. This inking mechanism may be of any usual or desired construction. In the construction illustrated, such mechanisms include an ink 45 fountain 25, fountain roll 26 and vibrating ductor 27 which delivers to a distributing cylinder 28, suitable distributing rolls 29 being provided for evening up the ink, the ink being delivered to the form cylinder by 50 form rollers 30.

While the invention has been shown and described in connection with a rotary ma-

chine in which two decks of two printing couples are mounted substantially in line, it will be understood that the invention is not 55 to be limited to such arrangement, but that it may be employed in various other relations and in various other types of machine without departing therefrom, and it is understood that such changes may be made. 60

What is claimed is:

1. In a printing machine, the combination with a plurality of printing couples, of an ink fountain and a single distributing cylinder to which ink is delivered from the 65 fountain, a pair of form rolls which deliver ink to the form member of one couple, a second pair of form rolls which deliver ink to the form member of the second couple, and means for reversing the direction of 70 rotation of one of the sets of rolls.

2. In a printing machine, the combination with a plurality of rotary printing couples, of an ink fountain and a single distributing cylinder to which ink is delivered from 75 the fountain, a pair of form rolls which deliver ink to the form cylinder of one couple, a second pair of form rolls which deliver ink to the form cylinder of the second couple, and means for reversing the direction 80 of rotation of one of the pairs of form rolls.

3. In a printing machine, the combination with a plurality of rotary printing couples, of an ink fountain, a distributing cylinder to which ink is delivered from the 85 fountain, a pair of form rolls which take ink directly from the distributing cylinder and deliver it to the form cylinder of one of the couples, a pair of form rolls for delivering ink to the form cylinder of the other 90 couple, and a pair of intermediate rolls between the distributing cylinder and the second pair of form rolls, said intermediate rolls being arranged to take the ink delivered to the distributing cylinder before 95 the distributing cylinder delivers to the first pair of form rolls.

In testimony whereof, I have hereunto set my hand, in the presence of two subscribing witnesses.

LOUIS A. SCHMIDT.
